UNITED STATES PATENT OFFICE.

MICHAEL G. DELANEY, OF DETROIT, MICHIGAN, ASSIGNOR TO THE NORTHERN SALES CO., OF TOLEDO, OHIO, A CORPORATION OF OHIO.

ADJUSTABLE CASING FOR FILM-REELS.

1,144,695.

Specification of Letters Patent. Patented June 29, 1915.

Application filed February 16, 1914. Serial No. 818,911.

To all whom it may concern:

Be it known that I, MICHAEL G. DELANEY, a citizen of the United States of America, residing at Detroit, in the county of Wayne 5 and State of Michigan, have invented certain new and useful Improvements in Adjustable Casings for Film-Reels, of which the following is a specification, reference being had therein to the accompanying 10 drawings.

In the operation of moving picture machines wherein a loaded film reel is placed in the casing and the flexible film strip is drawn off therethrough by suitable mechanism, arrangement is made ordinarily for the delivery of the film from a standard or conventional type of reel having a film drawn off from its periphery. Ordinarily 15 in shipping reels from the makers to the place of exhibits, this type of side delivery reel is employed and consequently when the machine is first used this reel is mounted in the casing and unloaded therefrom. If however the machine is adapted for center delivery reels it is necessary to rewind the film 20 from the shipping reel upon the center delivery reel before the film can be used.

This invention relates to a moving picture machine and more particularly to a film 30 reel casing or magazine therefor which is adapted to receive either a standard or conventional reel or a center delivery reel and is adjustable to provide for the proper withdrawal of the film from either type.

The invention consists in the matters hereinafter set forth and more particularly pointed out in the appended claims.

In the drawings, Figure 1 is a view in front elevation, partially broken away, of a film reel casing or container that embodies features of the invention disposed for delivery of a film from a shipping reel or standard type delivery reel; Fig. 2 is a view in elevation of the casing disposed for the delivery of a film from a center delivery reel; Fig. 3 is a view in front elevation of the casing disposed as shown in Fig. 2, the parts being broken away to give clear view; and Fig. 4 is a view in detail of a supporting bracket.

Referring to the drawing a casing 1 of suitable material and design has a cover 2 whereby a reel indicated diagrammatically at 3 in Fig. 1 may be inserted on a suitable spindle or like device so that a film indi-

cated at 4 may be drawn off therefrom through guide rolls 5 that are disposed at a lateral delivery opening in the lower face of the casing. The reel supporting member may be provided with driving mechanism 60 such as indicated, largely diagrammatically, at 6 and 7, such mechanism being carried on a suitable bracket 8 and being operated by a motor 9 that is mounted on the exterior of the casing. This reel driving mechanism 65 constitutes no part *per se* of this invention and therefore is neither illustrated nor described in detail.

A standard 10 of appropriate design is supported on a projecting machine frame 11 70 and carries at its upper end a bracket 12 that is adjustably secured by cap screws 13 or the like and slots 14 so as to be shiftable longitudinally on the support. A depending stem 15 is secured in a lug 16 or extension of 75 the casing 1 that is disposed along the lower margin of the back thereof, the body of the stem being adapted to engage in an opening 17 of the member 12 or corresponding aperture 18 thereof.

When the parts are in the position indicated in Fig. 1 that the reel 3 of side delivery type therein and the film 4 passing between the rollers 5, the stem 15 is inserted in the opening 18 and a feather pin 19 or stop engages a recess 20 in the side of the enlarged head 21 of the stem. This holds the casing rigidly in such position that the guide rolls 5 are in operative relation to the train of gearing indicated at 22 whereby the 80 film 4 is drawn off by the picture machine proper. The casing 1 is also provided with a slot or recess in the lower margin adjacent the cover 2 with a flanged tension roller 23 mounted thereon in such manner that when 85 a center delivery reel, such as indicated diagrammatically at 24 in Fig. 2, is mounted in the magazine, the film 25 thereof may be readily drawn out through the recess. When the casing is loaded with a reel of 90 this character the stud 15 is dropped into the opening 17 and a corresponding stem 26 on the bracket 16 engages the opening 18. This holds the casing at substantially right angles to the position in which it is locked 95 by the stop 19 and also in such relation to the gear train 22 of the picture machine that the film 25 is drawn smoothly over the roll 23 into register with the feeding mechanism. The method of mounting the roll 23 on the 100 110

casing 1 is immaterial although it is herein shown as carried on a pair of horizontally arranged members 27 that are shiftable in apertured lugs 28 whereby the tensioning effect of the roll 23 may be changed. The 5 details of the tensioning device are not indicated herein as they do not *per se* form a part of this invention, being claimed in my co-pending application, filed February 16, 10 1914, Serial No. 818,912.

As a result of this construction a casing is obtained whereby the standard shipping film reel of moving picture machine may be mounted on the latter in suitable position 15 for delivery and thereafter a center delivery reel on to which the contents of the standard reel may be drawn may replace the standard reel in the magazine and the latter be shifted to permit the delivery of the film 20 in proper relation to the feeding mechanism. This enables the use of either rim delivery or center delivery reels on the machine without the necessity of re-winding thus lessening the wear and tear on the films as well 25 as preventing the loss of time which has occurred by the rewinding process. Because of the adjustable features of the holder or member on which the casing is mounted the necessary alinement of the film is readily 30 secured and slight deviations may be properly taken care of.

Obviously, changes in the details of construction may be made without departing from the spirit of my invention and I do not 35 care to limit myself to any particular form or arrangement of parts.

What I claim is:—

1. In a moving picture machine including a projecting machine with gearing for 40 drawing off a picture film, a casing for film reels provided with means for detachably mounting such reels in the casing and with delivery openings for both center and side delivery reels with means for mounting the 45 casing on the frame in which the casing is adjustable for bringing either opening into operative registration with the gearing.

2. In a moving picture machine including picture projecting mechanism with gearing 50 for drawing a film therethrough, a casing for film reels having a delivery opening for side delivery reels and an opening for center delivery reels, and means for supporting the casing in operative relation to the gearing, the casing being adjustable in the supporting means for bringing either opening 55 into proper alinement with the gearing.

3. In a moving picture machine including film operating mechanism, a bracket adjustably supported on the machine, a film reel 60 casing adjustably mounted in the bracket and provided with film delivery openings for both side and center delivery film reels, and means for detachably locking the casing 65 in the supporting bracket with either open-

ing in proper registration with the film operating mechanism.

4. In a moving picture machine, a bracket detachably mounted thereon, a film reel casing, a stem on the casing adapted to detachably interlock with the bracket, film guiding rolls at an opening in the casing that are in operative registration with the mechanism of the machine when the stem is interlocked with the bracket, a film tensioning roller 70 on the casing at a delivery opening thereof, and a stud on the casing that is adapted to coöperate with the stem when engaging the bracket for holding the casing with the tensioning roller in operative relation to the 75 mechanism of the machine.

5. In a picture machine having film feeding gearing, a bracket adjustably supported on the machine, a reel casing, a stem on the casing adapted to interlock with the bracket 80 when the casing is in one position, a stud on the casing adapted to engage the bracket together with the stem for holding the casing in another position, film guiding members at one opening of the casing for drawing a film therefrom by the machine when the stem alone engages the bracket, and a tensioning roller on the casing at another 85 opening thereof adapted to guide a film drawn therefrom by the machine when the 90 casing is held by the engagement of the stud and stem of the bracket.

6. In a moving picture machine, means on the casing for rotatably securing film reels 100 therein, a stem for supporting the casing and bracket on the machine adapted to detachably interlock with the stem for holding the casing in position for delivery of a film from a side delivery reel mounted therein, a stud on the casing adapted to coöperate 105 with the stem for locking the latter detachably on the bracket for delivery of a film from a center delivery reel mounted therein, and guiding means mounted on the casing for controlling the movements of films 110 drawn from either type of reel.

7. In a moving picture machine, a main frame mechanism mounted thereon for operating a film, a bracket on the main frame, a film reel casing, means supported by the casing for operatively mounting a side and center delivery reels therein, supporting means for the casing detachably engaging the brackets for holding the latter in position for delivering a film to the mechanism 115 from either a side or a center delivery reel, and film guiding means on the casing for controlling a film delivery from either type 120 of reel.

8. In a moving picture machine, a main frame, film operating means on the main frame, a bracket adjustably supported on the main frame, a casing, means carried by the casing for operatively mounting both 125 side and center delivery reels therein, the 130

casing having openings for the delivery of films from either type of reels, a stem for supporting the casing in the bracket with the side delivery opening in operative registration with the film operating mechanism, and a stud on the casing coöoperating with the stem for holding the casing with the center delivery film opening in operative

registration with the film operating mechanism.

In testimony whereof I affix my signature in presence of two witnesses.

MICHAEL G. DELANEY.
